Design No 705—

George Holgett's Design for a Water Cooler.

Patented May 22, 1855—

Fig. 1.

Des. 705

George Hodgetts, of New York, N.Y.
Letters Patent, No. 705, Dated May 22nd 1855.

The schedule referred to in this Letters Patent, and making part of the same.

To all whom it may concern,

Be it known that I, George Hodgetts, of the City, County, and State of New York, have invented or produced, a new and useful Ornamental Design, for a Water-Cooler, and I do hereby declare that the following is a full, clear, and exact description of the same, reference being had to the accompanying drawings, forming a part of this specification, in which

Fig. 1, is a plan or top view; and

Fig. 2, a side elevation.

Similar letters of reference in each of the two

figures, indicate corresponding parts.

This design is intended to be worked in sheet metal, and may be produced either by the spinning or stamping process, as found desirable.

In its general character, it resembles a column or pillar.

A represents the body, B, the base, C, the top, and D, the cock of the Water Cooler. The body A, in its vertical section from the point a, near its upper extremity, to the point b, near its lower extremity, is straight, and from the point a, upward it diminishes in diameter, taking the form of a cima recta, and thus forming a neck c, which is encircled by mouldings d, e, f, of the character represented; and from the point b, to the base, it increases in diameter and takes the form of an ovolos, until it terminates in a fillet h, which connects it with the base B, at a point a short distance from its circumference. The body A, and base B, are embellished round their circumference with flutes, g, g, g, of the character shown in the horizontal fillet of the drawing. By thus fluting the body and base, raised, circular, conical, and square ornaments i, j, k, are formed, the latter of which are embellished by very shallow flutes l, l, as represented. A projection or raised ornament m, of the character shown, is also formed round the hole in which the cock D, screws. The top or cover, from its upper extremity to near its flange m, takes the form of a cima reversa, moulding o, and between the termination of . . . said moulding and the flange m, takes the shape of an ovolos, p, which terminates in a fillet q, as represented. It is also finished or tipped off, with an ornamental knob, r, which is apparently divided into four parts, and when seen from above, as in Fig. 1, resembles a rosette, and when seen from the side, as in Fig. 2, is of the form and character represented.

U.S. 705

383

What I claim as my invention, and desire to secure by
Letters Patent, is,

The design and configuration of the parts A, B,
C, represented in the accompanying drawings, and herein
described, forming a Watercooler.
